DESIGN FOR A DRESS

Joset Walker, New York, N. Y.

Application April 17, 1941, Serial No. 100,448

Term of patent 3½ years

To all whom it may concern:

Be it known that I, Joset Walker, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my new design.

Fig. 2 is the rear view of Fig. 1.

Fig. 3 is an enlarged fragmentary view of Fig. 1 illustrating the button and buttonhole trim, and

Fig. 4 is another enlarged fragmentary view of Fig. 1 illustrating the collar in buttoned position.

I claim:

The ornamental design for a dress, substantially as shown.

JOSET WALKER.
